UNITED STATES PATENT OFFICE.

ARCHIE DIMITOS AND GREGORY DIMITRI MICHAL, OF SYDNEY, NEW SOUTH WALES,
AUSTRALIA.

MACHINE FOR WASHING TABLE UTENSILS.

Application filed January 2, 1926, Serial No. 78,943, and in Australia February 11, 1925.

This invention relates to machines primarily intended for domestic use in the washing of plates, cups, saucers, cutlery, and other table ware, but usable also for the 5 washing of other articles.

In the accompanying drawing—

Fig. 1 is a vertical sectional elevation through the machine, the cradle having a tubular centre which is supported on a centre 10 post;

Fig. 2 is a fragmentary sectional plan view;

Fig. 3 is a detail sectional view on enlarged scale of the waste vent and plug;

Fig. 4 is a fragmentary sectional view 15 showing a modification in which the cradle is rotatably supported on a cone centre bearing and peripheral rollers; and

Fig. 5 is a fragmentary sectional view 20 showing an alternative method of fitting the driving crank and the driving spindle.

Referring to Figs. 1, 2, and 3:

10 are the sides and 11 is the bottom of an open top cylindrical vessel and 12 are 25 legs on which said vessel is mounted. 13 is a vent pipe connected by a union nut 14 to a liner flange 15 which is fixed on the bottom 11 of the vessel. 16 is an outflow vent in the bottom 11. 17 is a plug of hard

30 rubber provided with a seating 18 on the top end of the vent pipe 13, and 19 is a packing ring. 20 is a lever connected by a link 21 to the plug 17. The lever 20 is carried on a pivot pin 22 and the back end of it is

35 cranked and articulated to a push rod 23 which is extended beyond the side 10 of the vessel and is there fitted with a hand knob 24. 25 is a coiled spring sleeved over the rod 23 and set to force said rod inward

40 so as thereby to hold the plug 17 closed on its seating. When it is necessary to discharge the vessel, the valve is opened by pulling the hand knob outward; a latch member 32 in the form of a tooth on the

45 rod 23 latches behind the slot in the frame through which the rod passes. When this latch is released the valve is reclosed automatically by the spring 25. 26 is a lan-

50 tered foot piece fitted over the vent 16 and secured to the vessel bottom 11. A vertical post 27 is firmly footed in the foot piece 26 and this post is shaped at its top end to form a cone support bearing 60 for the

55 cradle 28 which is built on a flange 29 pro-

which is a free fit on the post 27. The cradle 28 is thus freely rotatable on its pivot bearing around the post 27. The structural arrangement of the cradle 28 is immaterial; the wire frame arrangement shown is a convenient one inasmuch as it permits table plates, saucers, and the like to be disposed on edge more or less tangentially to the centre 27. In the post 27 a bearing is formed for the inner end of a drive shaft 60 33; this drive shaft passes through a stuffing box 34 in the wall 10 of the vessel and its projecting end is fitted with a hand crank 35. On the inner end of it the drive shaft 33 carries keyed to it a bevel pinion 36 and 65 this bevel pinion meshes with a bevel wheel 37 which is rotatable on the post 27. 38 are paddles, two or more in number, arranged symmetrically and fixed to the bevel wheel 37. When the hand crank 35 is rotated, the rotation is communicated through the gear train 36—37 to the paddles 38 which are caused to revolve through water contained in the vessel, so as to bring the water into rapid circulation and cause it to surge upwards on the walls 10 by centrifugal action. 70 39 are splasher blades fixed on the inner wall of the vessel and projecting inwardly; these blades 39 are preferably inclined at a slight angle from the radial as seen best 75 in Fig. 2, and they may be erect or disposed more or less helically as suggested in Figs. 1 and 2. The best arrangement found is an alternation of blades, certain of them being erect blades such as 40 and the other 80 blades being inclined more or less helically. The number of the blades is not very material. In practice, six or more blades are used. At the top, the vessel wall 10 is finished in a cupped ring 42 into which the 85 rim portion of the lid 43 is set; splashing and overflowing of wash water is minimized by this arrangement. A conical collar 60 near the top of the wall 10 throws the upwardly spashed water back into the 90 centre of the vessel. A glass panel (not shown) may be fitted in the centre portion of the lid 43 if desired. 44 is a perforated pipe, the bottom end of which is brought out through a connection 45 into which water or steam may be supplied; water or steam supplied through this connection is directed in jets radially inward so as to lave the ware carried in the cradle 28 during the 95 washing operation. The cradle 28 may be 100 105 110

lifted out for loading and unloading. The rotational movement of the water which is splashed tangentially over the cage and the ware carried in it, operates to impart 5 a slow rotational movement to the cradle and facilitates the washing operation inasmuch as all sides of the ware are successively brought within the range of the splashing water proceeding from the several splasher 10 blades 39—40.

The alternative arrangement shown in Fig. 5 provides for the omission of the central post 27 and the tubular bearing 30. There is substituted for them a cone point 15 footstep 50 with a corresponding cup in the centre of the flange 29. The cradle is maintained in a vertical position by means of rollers 51 fixed on the sides of the vessel, 52 being a ring rail around the under 20 part of the cradle running on the rollers 51. In Fig. 5, an arrangement is shown for speeding up the shaft 33; in this case the crank 35 is not fixed directly on the spindle 33 but is keyed to a separate spindle 54 and that spindle carries a pulley 55 which is connected by a belt 56 to a small pulley

57 on the outer end of the spindle 33. There is a difference in degree only in all these cases in operation, which, in substance, is identical in that it consists in producing a 30 circular surge in the water, causing it to mount the sides of the vessel, race up the blades 39—40 and splash inwardly towards the centre of the vessel.

What we claim as our invention and desire 35 to secure by Letters Patent is:—

In a machine for washing tableware, a stationary cylindrical vessel 10, a fixed vertical post 27 centrally mounted in said vessel, with a cone shaped bearing 60 on the top 40 end of said post, a flanged tubular sleeve 30 removably mounted on said post, a rotatable wire cradle 28 supported by said flanged tubular sleeve, and means for rapidly swirling and splashing water in said vessel, 45 said cradle being slowly revolved by the swirling water.

In testimony whereof we affix our signatures.

ARCHIE DIMATOS.
GREGORY DIMITRI MICHAL.
